(57) CLAIM

I claim the ornamental design for the compact, as shown and described.

DESCRIPTION

FIG. 1 is a perspective view of the compact;

FIG. 2 is a top view of the compact;

FIG. 3 is a bottom view of the compact;

FIG. 4 is a front side view of the compact;

FIG. 5 is a right side view of the compact; and,

FIG. 6 is a rear side view of the compact.

The broken lines are shown for illustrative purposes only and form no part of the claimed design.
